UNITED STATES PATENT OFFICE.

THOMAS MITCHELL, OF CHESTER, PENNSYLVANIA, ASSIGNOR TO DANIEL EAGAN, OF PHILADELPHIA, PENNSYLVANIA.

ART OF HARDENING TREADS OF CAST-STEEL CAR-WHEELS.

SPECIFICATION forming part of Letters Patent No. 728,271, dated May 19, 1903.

Application filed June 20, 1902. Serial No. 112,424. (No specimens.)

To all whom it may concern:

Be it known that I, THOMAS MITCHELL, a citizen of the United States, residing in the city of Chester, in the county of Delaware and State of Pennsylvania, have invented certain new and useful Improvements in the Art of Hardening the Treads of Cast-Steel Car-Wheels, of which the following is a specification.

10 My invention relates to the hardening of the rims of cast steel car wheels, and its object is the provision of an economical, simple, and easily conducted, operation for accomplishing such result.

15 The general basis of my improvement consists in the application, through a suitable mechanical agency, of air under pressure to the rim or tread of a hot steel car wheel, while movement, preferably rotative, is contemporaneously imparted to one of said devices with respect to the other, so that the relation between the agency and the wheel is varied proportionately to said movement.

20 In the rotation of the wheel, for example, (in the particular form of apparatus herein described as employed, in which the wheel rotates), the different portions of its tread and the locality or point of discharge of the air constantly vary with relation to each other.

25 30 The locality of discharge of the air may, in the described apparatus, be considered as the inner circumferential mouth or opening of the boxing or casing.

35 Manifestly, the circumferential portions of the wheel are in the successive positions occupied by the wheel, in the rotation which the described apparatus imparts to such wheel, progressively brought opposite to all the successive circumferential portions of said mouth or opening, so that a given point of the wheel tread varies, proportionately to the relative movement as between the wheel and the casing, its relation to any given point of the inner opening or mouth of the boxing or casing.

40 45 Hence, although in the form of apparatus depicted the relation of the axis of the wheel to the axis of the casing is not varied in the operation of the parts, the relation between the tread of the wheel and the locality of the discharge of the air does vary as just described.

I speak of the opening or mouth of the boxing or casing which confronts the wheel tread, as the locality of the discharge of the air, inasmuch as the air introduced via the pipe *k* 55 and the distributor *m* to the boxing or casing acts through said opening or mouth against the wheel tread.

The employment of air as a hardening fluid for the treads of cast steel car wheels is not 60 only advantageous in the ease with which it may be supplied and controlled, and the simplicity of the apparatus involved, but particularly advantageous by reason of the very effective results which may be accomplished, 65 it being, by its use, in the manner hereinafter set forth, possible to produce any desired hardening in the treads of wheels operated upon, and in treating a large number of such wheels, to bring the rims of all to a uniform 70 hardness.

In the accompanying drawings I illustrate an apparatus which may be conveniently employed in carrying my invention into practice. The apparatus may, of course, be constructed otherwise than as shown in said drawings.

In the drawings,

Figure 1 is a view in side elevation, partly in section, of an apparatus by the aid of which 80 my invention may be practiced.

Figure 2 is a top plan view of the same.

The construction of the apparatus shown in the accompanying drawings is as follows:

a is a rotatable carrier, consisting of a supporting plate, of diameter approximately the same as that of a wheel to be operated upon—and an axial depending stem, which extends through a pair of sleeves *b*, carried on any suitable supports *c*, and with respect to which 85 sleeves said stem, with its supporting plate, is free for revolution.

Such revolution may be conveniently imparted to the carrier by providing the lower end of the stem with a driven bevel gear *d*, 95 engaging with a driving bevel gear *e*, supposed connected with any convenient source of power.

The supporting plate or head of the rotatable carrier is of circular plan, and is arranged in an opening in which it snugly fits, 100 free for revolution, in a floor or platform *f*,

the upper face of the supporting plate being conveniently flush with that of the floor or platform.

A depending annular lip *g* is arranged at 5 the edge of the opening in the platform *f*. *h* is an annular wall, conveniently located in a position in which it is concentric with respect to the carrier, upon said floor *f*, said wall having an inwardly extending lip *i* arranged above the floor a distance approximating the thickness of a car wheel.

As will be observed, the portion of the floor *f* in the vicinity of the carrier, the wall *h*, and the lip *i*, together constitute an annular 15 three sided or hood-like boxing, having an inwardly facing endless opening, of breadth approximately equal to the thickness of a car wheel at its rim, the arrangement being such that the rim of a car wheel placed upon 20 the rotatable carrier, will face said opening, and with the marginal portion of the supporting plate of the rotatable carrier, very nearly close it.

If desired, said annular hood like boxing 25 may be strengthened by the annular braces *j* as shown in Figure 1.

k is a supply pipe assumed to be in communication with a source of supply of air under pressure, which pipe extends through a 30 suitable opening to the interior of the annular hood-like boxing, where it is in communication with an annular tubular distributor *m*, the inner face of which is provided with a large number of small escape openings.

35 As will be understood from a contemplation of the drawings, the air, entering the distributor through the supply pipe, will emerge through said escape openings in a great number of small jets directed toward the rim or 40 tread of the wheel *n*.

In the operation of the apparatus, the wheel, preferably but not restrictively at about a cherry red heat, is placed on the carrier and the latter caused to rotate. The air pressure 45 is turned on through the supply pipe *k*, and thereupon entering the distributor escapes from it in jets, playing against the rotating wheel.

The arrangement is preferably such that 50 the air escapes from the distributor more rapidly than it escapes through the crevices *o* and *p*, and consequently it accumulates in the hood, forming an air expansive cushion therein, which, as stated, presents against the rim 55 or tread of the wheel.

Although said mass or cushion of air in the hood may, when it has become sufficiently dense, somewhat interfere with the direct action of the jets, as such, against the rim of the 60 wheel, said jets will, notwithstanding, have a tendency constantly to aid in forcing the mass of air in the boxing against the rim of the wheel,—and, apart from the foregoing function, the distribution of the jet openings 65 of the distributor throughout its inner cir-

cumferential face, occasions such a uniform distribution within the boxing of the air entering through the pipe *k* as tends to maintain an even pressure of the air against all parts of the wheel rim.

As will be obvious, in the rotation of the wheel, during the time the air is being charged into the boxing, all parts of the wheel tread successively confront, rapidly and repeatedly, all the regions of the opening of the boxing, 75 consequently, between the movement of the wheel and that of the air, a very intimate contact is established between said tread and air, and as a result, great uniformity of the action of hardening is insured.

For ordinary purposes air at atmospheric temperatures may be charged to the distributor, but, if desired, air at a lower temperature may be charged thereto for the purpose of accelerating or increasing the effectiveness 85 of the operation.

The apparatus herein described forms the subject of a separate application for Letters Patent duly executed by me and filed contemporaneously herewith as Serial No. 112,425.

It is, of course, to be understood that the air employed need not be perfectly dry, but may be more or less saturated with any suitable liquid such as water or oil, or with such air may be commingled any ingredient which 95 may be found useful for the purpose.

I find that the hardening action due to the carrying of the air against the tread of the wheel is most perfectly accomplished when the operation herein described, beginning as 100 stated, preferably when the wheel is at about a cherry red heat,—is continued until the wheel is cold.

Manifestly when it is required to produce wheels not of the greatest hardness as to 10 their rims, the operator in charge of the machine will turn off the air before the casting becomes cold.

In other words, by regulating the length of exposure of the wheel to the air, the hardness 11 of the tread may be correspondingly and accurately regulated.

Having thus described my invention, I claim—

1. The improvement in the art of hardening 11 the treads of cast steel car wheels which consists in rotatively moving a wheel and in the application to the tread of such wheel, while such wheel is hot, and during its movement, of air under pressure.

2. The improvement in the art of hardening 12 the treads of cast steel car wheels, which consists in rotating said wheels while hot and, during such rotation, discharging jets of air, under pressure, against such treads, the jets being confined within an inclosure across an opening in which the wheel tread presents.

3. The improvement in the art of hardening 13 the tread of a cast steel car wheel, which consists in maintaining the tread of said

wheel, while hot, in contact with a cushion of confined air under pressure and occasioning the rotation of said wheel.

4. The improvement in the art of hardening the tread of a cast steel car wheel, which consists in rotating said wheel, while hot, maintaining the tread of said wheel during such rotation at the mouth of an annular inclosure, and discharging under pressure with 10 in said inclosure a series of jets of air.

5. The improvement in the art of hardening the tread of a cast steel car wheel, which consists in rotating said wheel with its tread in contact with a mass or cushion of air under pressure, and contained within an annular hood or boxing, said mass or cushion of air being supplied by discharging air within said hood or boxing, in jets, at a multiplicity of points, said jets being directed against the 20 tread of the wheel.

6. The improvement in the art of hardening the rims of cast steel car wheels, which consists in moving said wheels and in subjecting them at an elevated temperature, and 25 while moving, to the action of air under pressure, the subjection of said wheel to said air being continued until the wheel is cold.

7. The process of hardening the tread of a metal car wheel, which consists in subjecting 30 the tread of such a wheel, while said wheel is hot, to the action of air, partially confined

and under pressure, and contemporaneously varying the relation which said wheel tread bears to the partially confined air.

8. The process of hardening the treads of 35 metal car wheels, which consists in subjecting the tread of such a wheel, while said wheel is at an elevated temperature, to the action of compressed air, the subjection of said wheel tread to said air being continued until 40 the wheel is cold, and in varying the relation between a selected point of said wheel tread and the locality of the discharge of the air, during said operation.

9. The process of hardening the rims of 45 metal car wheels, which consists in subjecting the tread of a wheel, while said wheel is at an elevated temperature, to the action of air under pressure, the subjection of said wheel to said air being continued until the 50 wheel is cold, and during said operation, in progressively varying the relation between said wheel tread and the locality of discharge of the air.

In testimony that I claim the foregoing as 55 my invention I have hereunto signed my name this 12th day of June, A. D. 1902.

THOMAS MITCHELL.

In presence of—

THOS. K. LANCASTER,
S. SALOME BROOKE.
